CLEANSING DEVICE FOR GASIFICATION
BURNER NOZZLES

Herman Ekström, Stockholm, Sweden

Application October 4, 1940, Serial No. 359,668
In Sweden October 20, 1939

3 Claims. (Cl. 158—120)

The present invention relates to liquid fuel gasification burners of the known kind comprising a nozzle housing provided with a bore communicating with a supply channel for gaseous fuel, the burner nozzle being removably secured to the housing in alignment with the bore and having an outlet orifice for the gaseous fuel, a valve adapted to control and close the outlet of said supply channel and having a spindle screwed into the housing and carrying a pinion, the teeth of which protrude into the bore through an opening in the wall of the bore, said pinion being in mesh with a rack carrying a cleansing needle at the one end, which needle is in alignment with said orifice and adapted to be inserted into and withdrawn from the orifice for cleansing the latter upon turning the aforesaid valve in the one or the other direction.

The manufacture of gasification burners of this type is connected with the difficulty of mounting the rack carrying the cleansing needle in a correct engagement with the pinion of the valve spindle. It is desirable that the rack should be fitted in some definite relation to said pinion, so that for example when the valve is fully closed, the cleansing needle should have fully penetrated through the nozzle orifice, and that when opening the valve the cleansing needle should gradually be withdrawn from the orifice and be fully withdrawn when the valve is fully open.

It is obvious that this can be effected only if the engagement between the rack and the pinion is a definite one, that is to say, when the valve for example is closed, a certain tooth of the pinion should be in engagement with certain teeth of the rack, and the cleansing needle should at the same time have penetrated the orifice to the full extent. To effect such a correct engagement when assembling the burner or changing the rack, it has hitherto been necessary to remove the valve spindle, then to insert the rack into the bore and hold the same so that a correct engagement may in some way or other be established when the valve spindle is again screwed into the housing. This work has proved to be very tedious and troublesome and to require quite a lot of time, in fact this step in the manufacture of the burners has proved to be one that slows down the rate of manufacture far too much.

The object of the present invention is to develop means by which this step in the manufacture may be greatly hurried, and the rack carrying the cleansing still be automatically brought into correct engagement with the pinion of the valve spindle. The novel means according to the

invention is such that the valve spindle does not need to be removed but should be brought to its closing position before the rack is inserted into the bore of the housing.

According to the invention this is effected thereby that the other end portion (opposite to the needle) of the rack, which is inserted into the bore, has its face opposite to the toothed face obliquely cut off narrowly towards the end of the rack so as to enable the rack, when inserted into the bore, to be so tilted to an oblique position that at least one tooth on said end portion may pass the pinion and the succeeding tooth of the tilted rack will abut against and be stopped by the pinion, whereupon the rack, when brought to a position parallel with the linear axis of the bore, will be in a correct engagement with the rack.

An embodiment of the invention is illustrated on the accompanying drawing.

Fig. 1 shows a side view of a gasification burner, the parts referring to the invention being shown in section. Fig. 2 shows a section of said parts taken perpendicularly to the section shown in Fig. 1. Fig. 3 shows the rack provided with the cleansing needle, seen from the side opposite to the teeth. Fig. 4 shows a section along the line IV—IV in Fig. 2. Figs. 5, 6, and 7 show sections similar to that in Fig. 2 with the rack in various positions during the insertion into the bore of the nozzle housing.

As shown in Fig. 1, the nozzle housing 1 is provided with a bore 2, into which the rack 4 provided with the cleansing needle 3 is intended to be inserted.

The rack has the one end, being opposite to the cleansing needle, obliquely cut off at 5, on which oblique portion a projection 6 is provided in the shown embodiment, the projection in the shown case consisting of a ball. Into an opening in the one side of the bore the teeth of a pinion 7 protrude, the pinion being secured on a spindle 8 provided with a valve controlling the gas inlet. On the opposite side of the bore a longitudinal groove 9 is made, which groove ends approximately on a level with the linear axis of the valve spindle.

The insertion of the rack into the nozzle housing is effected in the following manner. When the burner nozzle 10 has been screwed off, the rack 4 is inserted in a tool 11 adapted to facilitate the insertion so that an angle β (Fig. 6) is formed between the linear axes of the tool 11 and the rack. In this position the rack is now inserted into the nozzle housing 1 in such a way

that the ball-shaped projection 6 engages the groove 9 in the side of the bore 2.

Fig. 7 shows how the first tooth of the rack has been able to pass the pinion, whereas the second tooth abuts against the top of a tooth on the pinion and prevents the further insertion downwards of the rack.

The ball 6 and the groove 9 guide the insertion of the rack. Fig. 7 shows that when the rack abuts against the pinion, the ball 6 has reached the bottom end of the groove, and the angle between the rack and the axis of the bore has been reduced to α .

An effort to further insert the rack causes the latter to be turned automatically to a position parallel with the axis of the bore, the ball 6 then leaving the groove 9, and the rack will be brought to the final position shown in Fig. 2, in which the rack and the pinion are in the desired correct engagement. When the above described operation is undertaken, the valve spindle 8 should occupy the position of closure, as being a definite position, in which the teeth protruding into the bore 2 occupy predetermined positions. When the burner nozzle then has been screwed onto the housing again, the device is ready for use.

The lower end of the groove 9 has been shown rounded on the drawing, but said end may of course instead be shaped as a straight inclined surface, along which the projection 6 slides downwards in the last part of the downward motion of the rack.

Having now particularly described the nature of my invention and the manner of its operation what I claim is:

1. A cleansing device for gasification burner nozzles comprising, a nozzle housing, a bore in said housing, a nozzle having an outlet orifice for the gaseous fuel and removably secured in said housing in alignment with said bore, a supply channel in said housing for the gaseous fuel, said channel communicating with said bore, a valve adapted to control and close the outlet of said channel, said valve having a spindle being 40 screwed into said housing, a pinion on said

spindle, an opening in the side of said bore, the teeth of said pinion protruding through said opening into said bore, a rack mounted in said bore, the teeth of said rack being in mesh with the teeth of the pinion, a cleansing needle at the one end of said rack, said needle being adapted to be inserted into and withdrawn from said orifice for cleansing purposes by turning said valve, and in which the other end portion of said rack having its face opposite to the toothed face obliquely cut off, and narrowing towards the end of the rack so as to enable the rack, when inserted into the bore, to be so tilted to an oblique position that at least one tooth on said end portion may pass the pinion and the succeeding tooth of the rack will abut against and be stopped by the pinion, whereupon the rack when brought to a position parallel with the axis of the bore will be in mesh with the pinion.

2. A cleansing device for gasification burner nozzles according to claim 1, and in which a projection is provided on the obliquely cut off portion of the rack, and a longitudinal groove is made in the side of the bore, into which groove said projection is to be inserted for guiding the rack when the latter is inserted into the bore, said groove ending approximately on a level with the linear axis of the valve spindle so that the projection when leaving the groove will automatically bring the rack to a position in mesh with the pinion.

3. A cleansing device for gasification burner nozzles according to claim 1, having a projection upon the obliquely cut off portion of the rack, and having a groove made in the side of the bore for receiving said projection in order to guide said rack when the latter is inserted into the bore, said projection including a ball secured to said rack, and said groove terminating approximately on a level with the linear axis of the valve spindle so that said projection when leaving said groove will thereby automatically shift the rack into a position in which said rack meshes with the pinion.

HERMAN EKSTRÖM.
